UNITED STATES PATENT OFFICE.

ETHEL MELTON, OF ATLANTA, GEORGIA.

CHILD'S BED.

Application filed November 12, 1924. Serial No. 749,457.

To all whom it may concern:

Be it known that I, ETHEL MELTON, a citizen of the United States, residing at Atlanta, in the county of Fulton and State of Georgia, have invented certain new and useful Improvements in a Child's Bed, of which the following is a specification.

This invention relates to improvements in children's beds or cribs and has for its principal object to provide a simple and efficient means whereby the same may be associated with a large bed.

One of the important objects of the present invention is to provide a child's bed which is adapted for slidable movement below the bottom of a large bed with which the same is associated whereby the child's bed may be readily set up for use, the child's bed being adapted to be folded when not in use so as to conceal the same under the large bed.

A further object of the invention is to provide a child's bed of the above mentioned character, wherein means is associated therewith for adjusting the same vertically so that the mattress on the child's bed may be disposed substantially flush with the mattress on a large bed with which the child's bed is associated.

A still further object of the invention is to provide a child's bed of the above mentioned character, wherein the same may be readily and easily secured in position on the side rails of a large bed so that the child's bed will be adapted for lateral sliding movement with respect to the large bed.

A still further object is to provide a child's bed of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a perspective view of the child's bed embodying my invention showing the same in an extended position with respect to a large bed and ready for use.

Figure 2 is a detail perspective view of the drawer and the collapsible bed carried thereby.

Figure 3 is a detail perspective view showing the drawer extending partly beyond the

side of a large bed with the child's bed in a collapsed position.

Figure 4 is a fragmentary detail of the track and the rollers carried by the drawer cooperating therewith, and

Figure 5 is a detail perspective view of the track sections.

In the drawings wherein for the purpose of illustration is shown the preferred embodiment of my invention, the numerals 1 and 2 designate a pair of track sections, the same being supported in parallel spaced relation by means of the hinged connections 3 and 4 which are secured at their outer ends 70 to the upper portions of the attaching brackets 5 each of which is secured to the respective ends of the track sections in the manner clearly illustrated in Figure 5. The upper end of each of the brackets terminates in a lateral extension 6 and the extensions co-operate with the side rails 7 of a large bed 8 in the manner as clearly illustrated in Figure 3. The track sections 1 and 2 are thus disposed transversely of the bed 8 and below the side rails thereof for the purposes hereinafter to be more fully described.

A substantially rectangular shaped drawer 9 is adapted for slidable movement below the bed 8 and to this end, the sides of the drawer 9 carry the hangers 10 which support the rollers 11, the same being adapted for engagement with the tracks 1 and 2 in the manner as clearly illustrated in the drawings. An additional roller 12 is supported on each of the sides of the drawer 9 adjacent the inner end thereof for engagement with the under side of the respective track sections whereby the displacement of the rollers 11 from the track sections is prevented. Suitable handles 13 are carried by the respective ends of the drawer 9 to facilitate the sliding movement of the same with respect to the bed 8.

A longitudinally extending partition 14 is provided in the drawer 9 adjacent the inner side thereof whereby a relatively large compartment 15 and a small compartment 16 are formed. A child's bed designated generally by the numeral 17 is adapted to be supported within the compartment 15 of the drawer 9 while the compartment 16 provides a means for receiving the usual bed linen or the like for the child's bed.

The child's bed 17 comprises a frame 18 having the usual spring 19 supported in the bottom thereof. The inner side of the

child's bed being open as more clearly illustrated in Figures 1 and 2. Wire sections 20 and 21 are hingedly associated with the upper edges of the ends of the frame 18 and a similar section 22 is hingedly associated at its lower edge with the upper edge of the sides of the frame 18, the wire sections being adapted to be supported in an upright position when the bed is in an assembled position by any suitable means such as is shown at 23. When the bed 17 is not in use, the wire sections 20, 21 and 22 are folded into the position shown in Figure 3 so that the same will not interfere with the sliding movement of the drawer 9 with respect to the bed 8.

The child's bed 17 is adapted for vertical adjustment within the compartment 15 so that the same may be raised to any desired height preferably for the purpose of causing the mattress in the child's bed to lie substantially flush with the mattress of the large bed 8. The adjusting means includes a pair of slotted links shown at 24, a pair of such links being pivotally secured at their lower ends to the sides of the compartment 15 of the drawer 9 as illustrated at 25. The slot in each of the links 24 is illustrated at 26 and cooperating therewith are a series of notches 27. Suitable pins or the like shown at 28 extend from the ends of the frame 18 of the child's bed 17 and are adapted for slidable movement within the slot 26 of the respective links 24 and are further adapted to be seated in the notches 27 for supporting the child's bed at the desired height when the same is in use.

When the child's bed is not in use, the same is disposed within the compartment 15 of the drawer 9 in a collapsed position in the manner clearly shown in Figure 3 and the door is adapted to be supported on the track sections 1 and 2 below the large bed 8 so that the drawer 9 and the collapsible child's bed associated therewith are entirely concealed. When it is desired to use the child's bed, the drawer 9 is moved outwardly from the large bed 8 until the inner side of the child's bed is free of the adjacent side rail of the large bed 8. The child's bed is then raised to an operative position and assembled by swinging the wire sections upwardly and securing the same in assembled relation. After the pins 28 have been set in the desired notches 27 of the slotted links 24, the drawer 9 is moved inwardly with respect to the large bed 8 until the open side of the frame of the child's bed comes in contact with the side rails of the large bed. A further inward movement of the drawer 9 will cause the child's bed 17 to swing upwardly

on the pivots 25 which supports the slotted links 24 so that the links 24 will assume a substantially vertical position. In this manner, the child's bed will be supported in a rigid position adjacent the side of the large bed 8 as in the manner shown in Figure 1. Supporting legs 29 are carried by the bottom of the drawer 9 and are adapted to be swung into an operative position when the drawer is in its outermost position with respect to the large bed 8.

As the side of the child's bed 17 which is adjacent the large bed 8 is opened, the occupant of the large bed may have ready access to the infant or child occupying the bed 17 without causing any discomfort to either person.

The provision of a child's bed of the above mentioned character, which is adapted to be associated with a large bed in the manner above described will obviate the necessity of making any alterations to a large bed in order to support the child's bed thereon and furthermore when the child's bed is not in use, the same may be easily disposed in a concealed position under the large bed.

While I have shown the preferred embodiment of my invention, it is to be understood that various changes in the size, shape and arrangement of parts may be resorted to without departing from the spirit of the invention and the scope of the appended claims.

Having thus described the invention, what I claim is:

1. In combination, a supporting structure, two pairs of links, one pair pivoted at each end of the supporting structure, each link provided with a longitudinally extending slot having a plurality of notches on one side thereof, and a bed having pins projecting from its ends for engagement in the slots of the links.

2. In combination, a supporting structure, an auxiliary supporting structure slidably mounted in the first supporting structure and disposed therebelow, a plurality of links pivoted to the auxiliary supporting structure, a pair at each end thereof, each supporting link provided with an elongated slot having a plurality of notches to one side thereof, and a bed having pins at its ends receivable in the slots of the links so that it may be housed in the auxiliary supporting structure under the first supporting structure, or the auxiliary supporting structure may be pulled outwardly to the side of the first supporting structure, and the bed raised by swinging the links upwardly.

In testimony whereof I affix my signature.

ETHEL MELTON.
